UNITED STATES PATENT OFFICE.

CHARLES D. FULLER, OF LATROBE, PENNSYLVANIA.

REVERSIBLE OPEN-HEARTH FURNACE.

1,362,412.

Specification of Letters Patent. Patented Dec. 14, 1920.

Application filed July 8, 1920. Serial No. 394,771.

To all whom it may concern:

Be it known that I, CHARLES D. FULLER, a citizen of the United States, residing at Latrobe, in the county of Westmoreland and State of Pennsylvania, have invented new and useful Improvements in Reversible Open-Heart Furnaces, of which the following is a specification.

The invention relates to improvements in open hearth reversible furnaces.

The object of the invention is to improve the construction of reversible open hearth furnaces and to provide simple, practical and efficient means for closing the side passages to the stack after the metal has been melted to retain the heating units within the furnace for assisting in maintaining the metal in the furnace in proper condition until the same is drawn off or otherwise removed from the furnace whereby a material saving in fuel is effected and the melted metal maintained in a proper condition after melting with less fuel than heretofore.

It is also an object of the invention to provide means for reversing the circulation through the furnace and the passages thereof after the side passages have been closed to the stack so that perfect condition of the metal may be maintained with the usual operation with respect to the reversal of the furnace.

With these and other objects in view, the invention consists in the construction and novel combination of parts hereinafter fully described, illustrated in the accompanying drawings and pointed out in the claims hereunto appended, it being understood that various changes in the form, proportion, size and minor details of construction, within the scope of the appended claims, may be resorted to without departing from the spirit of the invention or sacrificing any of the advantages thereof.

In the accompanying drawings, in which like numerals of reference designate corresponding parts in the several figures:

Figure 1 is a horizontal sectional view of a portion of an open hearth reversible furnace illustrating one form of the invention.

Fig. 2 is a horizontal sectional view of the same taken substantially on the line 2—2 of Fig. 1.

Fig. 3 is a transverse sectional view on the line 3—3 of Fig. 1.

Fig. 4 is a horizontal view of a portion of

an open hearth reversible furnace showing another and simpler form of the invention.

Fig. 5 is a transverse sectional view of the same.

Referring particularly to the form of the invention illustrated in Figs. 1 to 3 inclusive of the drawings, 1—1 designate side passages of an open hearth reversible furnace of the standard type leading from the checker chambers 2 to the stack 3. The checker chambers are connected by the usual passages on the furnace body or furnace proper 4, and the open hearth reversible furnace is operated in the usual manner and reversed periodically.

In the original operation of the furnace, air enters the same through the air inlet 5 and the furnace is equipped with side dampers 6 and a stack hamper 7 and it has a butterfly valve 8 located in the connecting passage 9 connecting the side passages with the stack 3.

The furnace shown in Figs. 1 to 3 inclusive is equipped with an auxiliary air inlet 10 having a blower 11 provided with a pair of outlets 12 diverging forwardly and arranged at an angle to the side passages 1 so as to discharge forwardly into the same. The discharge outlets of the blower are shown in the form of tubes or pipes but they may be of any desired construction as will be readily understood and passage of the air through the same is controlled by dampers 13 located at the outer ends of the pipes or tubes 12 constituting the blower outlets. The arrangement of the blower outlets will enable a current of air to be directed forwardly at either of the side passages 1 for causing a positive circulation through the same in either direction. The side passages are connected in advance of and adjacent to the blower by an auxiliary transverse passage 14 equipped with side dampers 15 which are adapted to be closed in the original operation of the furnace but when the metal in the furnace has been melted, the dampers 6 and 7 leading to the stack are closed and the dampers 15 are open. One of the dampers 13 is also opened to establish a circulation through the side passages, the auxiliary transverse passage 14 and the passages leading from the checker chambers 2 to the furnace body of the furnace proper 4. This will retain the heat within the furnace and prevent the heat-

ing units from escaping to the stack and will enable the metal, by a less consumption of fuel than heretofore, to be maintained in proper melted condition without a lowering 5 of the temperature thereof until the metal is used.

The simpler form of the invention is illustrated in Figs. 4 and 5 of the drawings in which the entire area of the side passages 10 15 and a connecting passage 16 are utilized for the auxiliary circulation within the furnace after the side passages 15 have been closed to the stack 17. The furnace which is of the standard type, of which only the rear 15 portion is shown for convenience of illustration; the first portion being substantially the same as that heretofore described, is equipped with the usual side dampers 18, stack damper 19 and a butterfly valve 20 20 which is adapted to be arranged on a dead center transversely of the furnace as illustrated in Fig. 4 as well as in its usual position for reversing the furnace in the original operation of the same. The air enters at 25 the air inlet 21 and the furnace is equipped at opposite sides at the rear ends of the side passages 15 with blowers 22 having outlets or passage tubes 23 and controlling dampers 24 for enabling either of the blowers 30 to be operated for causing a circulation through the side passages 15 and the other passages of the furnace after the side passages 15 have been cut off from the stack. The cut off of the side passages to the stack 35 at the damper 19 will retain within the furnace a maximum amount of heat and will save a maximum amount of fuel for maintaining the metal after it has been melted in such condition without permitting a lowering 40 of the temperature thereof until the metal is used and a fresh charge applied to the furnace. The blowers 22 are alternately operated and when one is operated the damper 24 thereof is open and the damper of 45 the other blower 22 is closed. The direct blowing of the air across the furnace at the rear end of the passages 15 will produce a sufficient circulation through the furnace and enable a positive reversal of the circulation to 50 be produced periodically. The blowers 22 are arranged exteriorly of the side passages and other outlets 23 pierce the outer walls of the side passages. The dampers are located at the inner faces of the outer side walls of 55 the said passages 15. Any suitable means may be employed for operating the dampers.

What is claimed is:—

1. An open hearth reversible furnace including means for closing the side passages 60 to the stack, and means for causing a positive auxiliary circulation through the passages of the furnace while the said passages are closed to the stack.

2. An open hearth reversible furnace including means for closing the side passages 65 to the stack, means for causing a positive auxiliary circulation through the passages of the furnace while the said passages are closed to the stack, and means for reversing the auxiliary circulation through the pas- 70 sages of the furnace.

3. An open hearth reversible furnace including means for closing the side passages to the stack, and means for discharging a current of air into the furnace for producing 75 a positive auxiliary circulation through the passages of the furnace while the side passages are closed to the stack.

4. An open hearth reversible furnace including means for closing the side passages 80 to the stack, and means for discharging a current of air into the passages of the furnace at either side thereof for producing a positive circulation of air through the passages of the furnace while the said passages 85 are closed to the stack and for reversing the auxiliary circulation.

5. An open hearth reversible furnace including means for closing the side passages 90 to the stack, and blowers located each at opposite sides of the furnace and having means for controlling the same for discharging a current of air into the furnace at either side thereof for causing a positive auxiliary circulation through the passages of 95 the furnace while the same are closed to the stack and for reversing the auxiliary circulation.

6. An open hearth reversible furnace including means for closing the side passages 100 to the stack, and blowers located at opposite sides of the rear ends of the side passages and provided with controlling means and arranged to discharge across the rear ends of the said passages in either direction for 105 causing a positive auxiliary circulation through the passages of the furnace while the same are closed to the stack and for reversing the circulation.

7. An open hearth reversible furnace in- 110 cluding means for closing the side passages to the stack, and blowers located exteriorly of the rear ends of the side passages of the furnace and having outlets piercing the outer walls of the said side passages and ar- 115 ranged to discharge across the same in either direction and provided at the inner faces of the outer side walls of the said passages with dampers whereby a positive auxiliary circulation is produced through the passages 120 while the same are closed to the stack and a reversal of the circulation effected.

In testimony whereof I hereunto affix my signature.

CHARLES D. FULLER.
